(57) **CLAIM**

The ornamental design for an electronic acoustic device, as shown and described.

DESCRIPTION

FIG. 1 is a front view of an electronic acoustic device, embodying my new design.

FIG. 2 is a right side view of the electronic acoustic device.

FIG. 3 is a left side view of the electronic acoustic device.

FIG. 4 is a top view of the electronic acoustic device.

FIG. 5 is a bottom view of the electronic acoustic device.

FIG. 6 is a rear view of the electronic acoustic device.

FIG. 7 is a front view of the electronic acoustic device.

FIG. 8 is a cross-sectional view of the electronic acoustic device, taken at line 8-8 of FIG. 7; and,

FIG. 9 is a cross-sectional view of the electronic acoustic device, taken at line 9-9 of FIG. 7.
